CLOTH BEAM CLUTCH

William H. Bahan, Greenville, S. C.

Application November 3, 1939, Serial No. 302,743

3 Claims. (Cl. 139—308)

This invention relates to a loom attachment and more especially to a cloth beam clutch. Most looms are equipped with cloth rolls upon which the cloth is wound as it is woven by the loom. This cloth roll is driven by means of a sand roll through peripheral contact and the sand roll has the woven cloth passing over a portion of its periphery prior to being wound upon the cloth roll. As the roll of cloth becomes larger, its axis moves away from the sand roll axis against the pressure exerted by a suitable torsion spring. When the desired size has been attained the pressure of the spring is released so that the cloth roll can be doffed. It is then necessary to place a rod in the position previously occupied by the cloth roll to constitute an axis around which the next cloth roll is formed, which rod is pressed into engagement with the sand roll by a manually operated winding mechanism. Heretofore, great difficulty has been experienced in applying the proper initial pressure between the newly inserted rod and the sand roll. If too much initial pressure is exerted, then portions of the restraining mechanism will likely break before the roll of cloth is completed, because as has been stated, the torsion spring is a portion of the restraining mechanism, and as the roll grows larger, the pressure between the sand roll and the cloth roll will remain substantially the same with a slight variation.

It is therefore an object of this invention to provide a slip clutch in the cloth beam supporting mechanism which will prevent an excessive amount of initial pressure from being exerted between the sand roll and the cloth roll.

It is a further object of this invention to provide an apparatus of the class described with means for varying the pressure limits at which the slip clutch arrangement will operate.

Some of the objects of the invention having been stated, other objects will appear as the description proceeds, when taken in connection with the accompanying drawing, in which—

Figure 1 is a front elevation of a loom showing my attachment applied thereto;

Figure 2 is a vertical transverse sectional detail view taken along the line 2—2 in Figure 1;

Figure 3 is a transverse sectional detail view taken along the line 3—3 in Figure 1;

Figure 4 is a plan view taken along the line 4—4 in Figure 1;

Figure 5 is a vertical sectional view taken along the line 5—5 in Figure 1.

Referring more particularly to the drawing, the numeral 10 denotes suitable end frames which are joined together at their upper ends by a breast

beam 11, and at their lower ends by a strut 12. Rotatably mounted in the upper portion of the frame assembly is a sand roll 14 around which a sheet of cloth 15 is adapted to be moved after it has been woven by the loom. This sand roll is driven by suitable mechanism not shown, but the rate of travel of this roll is substantially the same as the rate of weaving of cloth. As has been stated, the cloth 15 passes around a portion of the periphery of the sand roll 14 from whence it is wound onto a cloth roll 18 which roll has as an axis of rotation, a rod 19. The cloth roll is driven by peripheral contact with the sand roll and is held in engagement with the same by a suitable mechanism which will be presently described.

The ends of the rod 19 are rotatably mounted in the upper ends of vertically disposed racks 20, said racks being slidably mounted in guide members 21, and these guide members 21 have their upper and lower ends secured to members 11 and 12, respectively. The rack members 20 are adapted to have their teeth mesh with pinions 23 on shaft 24, which shaft is rotatably mounted in the lower portion of guide members 21.

An intermediate portion of shaft 24 has a collar 25 secured thereon by means of a set screw 26, said collar having a pin 27 extending from its periphery to which one end of a torsion spring 28 is secured. This torsion spring is disposed around shaft 24 and its other end is secured to another pin 29, which extends from the periphery of the collar 30. Collar 30 encircles the hubs 31 and 32 of gear segments 33 and 34 respectively. These hubs and gear segments are placed together to form a completed gear, and it is by means of this collar 30 that the two segments are rotatably clamped in position around the shaft 24.

In order to vary the amount of pressure exerted between the collar, and the gear segments, the ends of the collar 30 have a bolt 35 securing them together with nuts 36, 37, and 38 threadably secured thereon for adjustment purposes. By adjusting the nuts 36, 37 and 38, the friction that exists between the hubs 31 and 32 and the inner periphery of the collar 30 can be varied to set the limit at which the slipping action will take place between the collar and the hubs. This is an important feature because when this slipping takes place during the positioning of the rod 19 against the sand roll at the beginning of a cloth roll, then the proper amount of pressure has been exerted.

The gear or pinion which comprises segments 33 and 34 is adapted to mesh with a worm 40

55

therebelow, which worm is fixedly secured around a shaft 41. The shaft 41 has its intermediate portion rotatably mounted in bracket 42, said bracket being supported by means of strut 12. On the other end of the shaft 41, a handle 43 is pivoted as at 44, so that when it is desired to raise or lower the rod 19, relative to the sand roll 14, it is only necessary to turn this handle. It will be noted by referring to Figures 1 and 4 that the shaft 24 also has a bearing 47 therearound at a point adjacent the right hand face of the gear which is made from segments 33 and 34. This bearing is secured to bracket 42 and serves to prevent the spring 28 from pushing the gear segments 33 and 34 longitudinally of the shaft 24.

It is therefore seen that when it is desired to place a rod 19 against the lower periphery of the sand roll to form an axis around which a new roll of cloth is to be wound, that the racks 20 must be lowered until the upper ends thereof are disposed about the same level as notches 21a. Then the ends of rod 19 are placed in the upper ends of the rack members 20 after which the handle 43 is turned until the pinions 23 advance the racks and the rod against the lower periphery of the sand roll 14. Of course, it is necessary to start the ends of the cloth around the rod 19 before operation of the loom is begun. When the proper pressure between the sand roll 14 and the rod 19 has been exerted, a slippage will take place between the hubs 31 and 32 and the collar 30, thereby preventing an excessive amount of initial pressure from being exerted and also preventing any subsequent breakage of the parts, such as the teeth in the gear segments 33 and 34.

When the proper initial pressure has been exerted between the rod 19 and the sand roll 14, the cloth roll 18 is then begun. As its diameter increases, the rod 19 and its associated racks 20 move downwardly, and at the same time the pinion 23 and shaft 24 will rotate against the resistance of spring 28. Since the pinion parts 33 and 34 are loose on the shaft 24, but are held in stationary position by worm 40, it is evident that slippage will take place between collar 30 and hubs 31 and 32 as the diameter of the cloth roll increases. Nevertheless, due to the slip clutch arrangement, the pressure between the sand roll and cloth roll will remain substantially the same at all times.

In the drawing and specification, there has been set forth a preferred embodiment of the invention and although specific terms are employed, they are used in a generic and descriptive sense only and not for purposes of limitation, the scope of the invention being set forth in the appended claims.

I claim:

1. In a loom having a cloth take-up roll and a sand roll for driving the cloth take-up roll, means for holding the cloth take-up roll against the sand roll comprising a pair of rack members for supporting the axis of the cloth take-up roll, a rotatable shaft having a pair of pinions thereon for engagement with the rack members for pressing the take-up roll against the sand roll, a third pinion rotatably mounted on the shaft, a friction clutch connected to said third pinion, a resilient connection between said clutch and the shaft, means for driving the third pinion for moving the racks upwardly and for holding the pinion against uncontrolled rotation, the friction clutch allowing the shaft to rotate relative to said third pinion when a predetermined pressure has been created between the sand roll and the take-up roll due to the increase in diameter of the take-up roll as the cloth is wound thereon.

2. In a loom having a sand roll driven by the loom, and also having an arbor on which a cloth take-up roll is formed, a pair of rack members for supporting the arbor, a shaft having a pair of pinions fixed thereon for moving the rack members upwardly to hold the cloth on the arbor in contact with the sand roll, means for rotating the shaft comprising a gear loosely mounted on the shaft, a worm meshing with the gear, a slip clutch associated with said gear a torsion spring disposed on said shaft and having one end secured to the slip-clutch and having its other end adjustably secured on the shaft, whereby when a predetermined pressure has been built up between the sand roll and the cloth take-up roll to force the rack members downwardly, rotation of the shaft relative to the rotatably mounted pinion will be permitted.

3. In a loom having a rod on which cloth is rolled after it is woven, said loom also having a driven sand roll for contacting the cloth on the rod for rolling the cloth on the rod, a pair of rack members for supporting the ends of the rod, said loom also having a shaft provided with pinions for engaging the rack members for raising and lowering the rack members, a split gear loosely mounted on said shaft, a worm meshing with said split gear for driving the same, means clampingly engaging the split gear, a torsion spring disposed around said shaft and having one end secured to the clamping means and having its other end adjustably secured to the shaft, whereby when undue pressure is created between the take-up roll and the sand roll, the shaft will be allowed to rotate relative to the split gear until the undue pressure is relieved.

WILLIAM H. BAHAN.
